CLAIM

The ornamental design of a digital player, as shown and described.

DESCRIPTION

FIG. 1 is a perspective view of a digital player according to an embodiment of my new design;

FIG. 2 is a top elevation view thereof;

FIG. 3 is a front plan view thereof;

FIG. 4 is a right side elevation view thereof;

FIG. 5 is a left side elevation view thereof;

FIG. 6 is a back plan view thereof; and,

FIG. 7 is a bottom elevation view thereof.

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.
